(57) **CLAIM**

The ornamental design for a vehicle headlight, as shown and described.

DESCRIPTION

FIG. 1 is a right front perspective view of a vehicle headlight showing the claimed design;

FIG. 2 is a left front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The short dash-long dash broken lines illustrate boundaries of the claimed design and form no part of the claimed design. The portions of the figures shown de-emphasized within the short dash-long dash broken lines form no part of the claimed design.

1 Claim, 8 Drawing Sheets
